MOTOR DRIVEN SWITCH

Filed Oct. 18, 1934

UNITED STATES PATENT OFFICE

2,112,044

MOTOR DRIVEN SWITCH

Riccard Pudelko, Zug, Switzerland, assignor to
Landis & Gyr, A.-G., a corporation of Switzerland

Application October 18, 1934, Serial No. 748,825
In Switzerland October 25, 1933

3 Claims. (Cl. 200—153)

The present invention relates to motor-driven switching apparatus, and more particularly to a motor-driven switch particularly adapted for use in connection with electrically-heated boilers for heating systems.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawing, referred to herein and constituting a part hereof, illustrates one embodiment of the invention, and together with the description, serve to explain the principles of the invention.

Of the drawing:

Figure 1 is a side elevation of a typical embodiment illustrative of the present invention, with the cover and certain other parts being shown in section, and

Figure 2 is a front elevation of the embodiment shown in Figure 1 with the cover removed.

The present invention has for its object the provision of a novel and improved motor-driven switching apparatus, particularly adapted for the control of power supplied to heating systems. Another object of the present invention is the provision of a motor-driven switching apparatus adapted to carry out a normal switching cycle, and provided with means for interrupting or modifying the normal action of the apparatus.

The present invention is particularly adapted for controlling the supply of electrical energy to electrically heated boilers where the power is supplied during off-peak periods at low rates and the water so heated is distributed for the heating of the house or other room as needed during the day. In accordance with the present embodiment of the invention, the power is controlled by means of a motor-driven switch controlled in accordance with a predetermined time cycle, and optionally operable manual means are provided for opening the switch after it has been opened by the motor and other optionally operable manual means for opening the closed contacts.

Referring now in detail to the illustrative embodiment of the invention, as shown in the accompanying drawing, there is provided a base plate 5 to which a cover 6 is fastened by means of screws 7. On the base plate 5 are mounted posts

8 which support a plate 9 carrying the switch-operating motor, the switch contacts and the switch-operating cams. As embodied, the switch comprises a pair of contacts 10 and 11, contact 10 being mounted on a block of insulating material 12 which is pivotally supported to the plate 9 by means of pivot pin 13 passing through the lower portion of the block, and contact 10 extends rearwardly to form a threaded terminal 14 at the rear of the block.

Contact 11 is resiliently and movably mounted by a spring 15 secured to the block 12 by means of screw 16, the rear end of the screw forming a terminal 17 at the rear of the block 12. The spring 15 is of a general U-shape, and its upper free end is attached to a rigid strap 18 carrying a cam roller 19.

When it is desired to provide a two-pole switch, a duplicate set of contacts 10 and 11 may be mounted to one side of the first pair of contacts 10 on the block 12, but inasmuch as these are duplicates, they are not described in detail but are shown in the drawing.

Motor means are provided for operating the switching apparatus and for this purpose the magnet 20 of a small Ferraris motor is mounted on the rear face of plate 9 and operates to rotate motor disc 21. Motor disc 21 is rotatably mounted by means of a shaft 22 in a jeweled bearing 23 and a journal 24. Shaft 22 carries a pinion 25 meshing with gear 26 which is mounted on shaft 27 to drive shaft 27 through a friction clutch 28 and against the tension of spring 29 which has one end 30 fixed to the shaft 27 about which spring 29 is coiled and its other end 31 fixed to a plate or bracket 32 fixed to the plate 9. An abutment 33 is mounted on the frame plate 9 and serves to limit rotation of the shaft 27 by cooperation with stop 34. Shaft 27 is provided with cams 36, corresponding in number to the number of switch poles, and these cams cooperate with the cam rollers 19 to open the switches against the pressure of the contact mounting springs 15.

Means are provided for manually effecting closure of the switches during the time they are mechanically open, and for this purpose a rigid strap 40 extends upwardly from the block 12. Strap 40 is provided with a bent end 41 co-operating with a latch member 42 mounted on a spring 43 which extends forwardly from the plate 9 and is secured thereto. This latch serves to hold the contact 10, the block 12 and the strap 40 in their normal position, as shown by the dotted lines. For raising the spring 43 to release

55

the latch 42 and allow the block 12 to move placing contacts 10 and 11 in contact with each other, a cam 45 is rotatably mounted immediately beneath the forward end of spring 43 by means of a shaft 46 carried in the cover 6 and connected to knob 47. A spring 48 serves to return the cam 45 to its normal position after the fingers are released from knob 47, while a stop 49 mounted on the knob 47 cooperates with a stop pin 50 mounted on the cover to limit rotation of the knob 47.

Means are provided for restoring the contacts 10 and 11 to their normal position and for this purpose a cam 52 is mounted on shaft 27 between the cams 36, and is adapted to cooperate with the rigid strap 40 to move it forwardly to an extent sufficient to latch it in its normal position. Thereafter, the contacts remain open until the cams 36 are moved to permit them to close.

Means are also provided for opening the contacts 10 and 11 after they have been closed by the operation of knobs 47, and for this purpose a cam 60 is mounted on a shaft 61 rotatable in the cover 6 and connected to knob 62. Cam 60 is returned to its normal position by means of spring 63, and is limited in its rotation by means of stops 64. A bar 65 is rigidly supported with respect to block 12 by means of a forwardly-extending spark shield 66, and is adapted to cooperate with cam 60 so that by rotation of cam 60, the block 12 is restored to its normal latched position, whereby contacts 11 are spaced from the cooperating contacts 10.

Stops 49 and 64 may be apertured so that the apparatus may be sealed to prevent its use by unauthorized persons.

A suitable terminal chamber 69 is provided through which the connections may be made to the switch contacts 10 and 11 as well as to the 40 windings of the motor magnet 20, and the supply of power to the motor magnets may be controlled by means of a suitable time switch or otherwise as desired.

During the operation of the switching device, 45 the contacts 10 and 11 are initially held out of contact with each other, but by rotation of the cams 36 caused by operation of the motor disc 21, the springs 15 cause these contacts to be moved together to close the circuit. Stops 33 50 and 34 limit rotation of the shaft 27 against the tension of spring 29, but after the current supplied to the motor magnet 20 is discontinued, the spring 29 permits the cams 36 to return to their

original position, at which time the contacts 10 and 11 are out of contact with each other.

When it is desired to close the heating circuit during a peak load period, it is only necessary for the customer to rotate the knob 47, thereby releasing the latch 42 and permitting the contacts to move into contact with each other. Thereafter, the contacts are restored to their normal latched position upon the next operation of the motor disc 21 or they may be previously restored 10 by turning the handle 62.

The invention in its broader aspects is not limited to the specific mechanisms shown and described but departures may be made therefrom within the scope of the accompanying claims 15 without departing from the principles of the invention and without sacrificing its chief advantages.

What I claim is:—

1. A switching apparatus including in combination a pivotally mounted contact, a second contact mounted for movement with and with respect to the first contact, means for releasably holding the contacts in a predetermined relative position, a rotary cam to move said second contact, manual means for releasing the first contact, a cam to move said first contact after manual release and manual means for moving said first contact in case the second cam means has not moved the first contact. 30

2. A switching apparatus including in combination a pivotally mounted contact, a second contact mounted for movement with and with respect to the first contact, a latch for holding said contacts against pivotal movement, a rotary cam to move said second contact, manual means for unlatching said first contact, a cam to restore said contacts to latched position, and manual means for alternatively restoring said contacts. 35

3. A switching apparatus including in combination a pivotally mounted contact, a second contact mounted for movement with respect to the first contact, a latch for holding said contact against pivotal movement, a rotary cam to space said contacts by movement of the second contact, 45 manual means for unlatching said first contact to close said contacts, a cam to restore said contacts to latched position after they are closed by the other manual means and manual means for restoring said contacts to open position prior 50 to closure by said cam.

RICCARD PUDELKO.
